UNITED STATES PATENT OFFICE.

FREDERICK ELLIOTT FISHER, OF SUDBROOK PARK, MARYLAND, ASSIGNOR TO
EUGENE K. PLUMLY, OF PHILADELPHIA, PENNSYLVANIA.

CHUCK.

1,387,844.

Specification of Letters Patent. Patented Aug. 16, 1921.

Application filed January 26, 1921. Serial No. 439,932.

To all whom it may concern:

Be it known that I, FREDERICK ELLIOTT FISHER, a citizen of the United States, residing at Sudbrook Park, county of Baltimore, and State of Maryland, have invented a new and useful Improvement in Chucks, of which the following is a full, clear, and exact description, reference being had to the accompanying drawings, which form a part 10 of this specification.

This invention relates to an improvement in chucks and more particularly to chucks for machines for making cylindrical or round boxes, such as are commonly known 15 as pill boxes.

The object of my invention is to provide a chuck of this character together with operating mechanism therefor, which is cheap of construction and assembly, and which is 20 provided with adjusting devices to compensate for slight inaccuracies in construction.

In machines of the class in which these chucks are used the blanks from which the boxes are formed, which blanks consist of 25 circular disks and rings which form the bottoms and the sides of the boxes, are fed successively to a rotary table under the chuck but in axial alinement therewith. The chuck which is continuously rotated is then lowered and expanded to engage the disk and hold it in contact with the table and also 30 to engage the interior of the ring, and when these parts are engaged by the chuck, the blanks together with the table are rotated 35 with the chuck.

After the blanks are positioned by the chuck, a gummed strip is placed thereon to secure the disk to the ring, and the chuck is then raised to release the partially formed 40 box and which is removed by a blast of air preparatory to feeding the next set of blanks under the chuck.

The precise nature of my invention will be best understood by reference to the accompanying drawings, which will now be described, it being premised, however, that various changes may be made without departing from the spirit and scope of my 45 invention as defined in the appended claims.

Figure 1 is a diagram illustrating the blank feeding and box forming elements.

Figs. 2 and 3 are detail sectional views of the devices for pressing the gummed strip into contact with the blanks.

Fig. 4 is a vertical sectional view through the chuck and its operating mechanism.

Fig. 5 is a perspective view of one of the chuck jaws.

Fig. 6 is a detail sectional view on the line 3—3 of Fig. 4.

Fig. 7 is a similar view on the line 7—7 of Fig. 4.

Fig. 8 is another similar view enlarged on the line 8—8 of Fig. 4.

Fig. 9 is an enlarged side view of the 65 chuck body with the jaws removed.

In the manufacture of cylindrical boxes on machines of the above type, the bottom forming blanks or disks A are stacked within a suitable cylindrical container at the side 70 of a table B rotatably mounted below the chuck hereinafter described, and which disks are successively fed from the bottom of the stack to the table B, by means of a reciprocal feeding slide C, see Fig. 1. The sides 75 of the boxes are formed of short cylinders or rings D which are placed on a continuously rotating table E between fixed curved guides E¹ or E², and are carried against a stop e by the moving table between a gate F 80 hinged at f, and in front of a reciprocal feeding slide G. H is a gummed strip feeding roller which draws a gummed strip h from a suitable source of supply, and which roller is slightly more than four times the 85 diameter of the box being made. This roller H is also provided with four cutters (not shown) spaced ninety degrees from each other to cut the continuous strip h into proper lengths to cover the boxes. J is a 90 strip turning and pressing roller which is moved into contact with the positioned blanks A and D on the table B, and the applied strip h, after the blanks are grasped by the jaws K of the chuck to press the strip 95 into contact with the blanks to secure the parts to each other; and also to turn the edge h¹ of the strip as shown in Fig. 2. In 100 this figure the roller is shown when moving from the box after the strip h has been applied. L is a turning tool for turning the edge h¹ of the strip h against the inside of the blank D, as shown in Fig. 3, after it has been turned laterally by the roller J. The turning tool L is adjustably carried by a bar 105 L¹ which is in turn carried by a rod L² which is actuated by the mechanism for actuating the chuck. M is a stop pin for the turning tool to prevent its downward movement beyond a predetermined limit when 110 the chuck is moved downward and which pin is removed as hereinafter described to

permit the tool to descend to turn the edge h^1 of the strip.

All of the above actuating elements are connected to operating mechanism and arranged to actuate said elements in timed relation to each other to form the body or cover of a box, which are counter parts of each other.

In the operation of the machine, the slide 10 C is first actuated to feed a bottom blank A from under the stack of blanks to the table B. The slide G is then actuated to place a blank D on top of the positioned blank A. Immediately after the blanks are positioned, 15 the chuck is lowered, together with the turning tool L. The chuck is lowered a sufficient distance to clamp the blank A between the ends of the jaws K and the table B, after which the jaws are spread to clamp the blank 20 D, and to rotate the parts about the axis of the chuck.

The downward movement and rotation of the chuck as well as the spreading of the jaws is effected by mechanism hereinafter 25 described, and which downward movement of the chuck also causes the downward movement of the turning tool L until it engages the stop M, through the medium of a spring, which spring completes the further downward 30 movement of the tool L when the pin M is withdrawn. After the blanks A and D are grasped and rotated by the chuck jaws, the roller H is moved into engagement with the blanks and is rotated one-fourth turn in 35 timed relation to the blanks to feed a section of the strip h to the blanks which is of sufficient length to cover the box, and the roller J is also moved into contact with the placed strip to press it into engagement with 40 the blank A, the side of blank D and turn the edge h^1 at right angles to the body of the strip as shown in Fig. 2. The pin M is then withdrawn laterally from the full line position to the dotted line position shown in 45 Fig. 4 to permit the turning in tool L to be moved to the position shown to turn the edge of the gummed strip against the inside of blank D. After the various elements have performed their functions, they are returned 50 to the positions shown in Fig. 1 and during the return of the chuck the jaws are first closed and then withdrawn to release the finished box, which is removed from the table B by a blast of air which is delivered 55 after the operations on the box are completed.

Mounted on the frame of the machine which supports the driving mechanism for the above actuating members are standards 60 10, and 11 is a split bearing thereon. Rotatably mounted in three bearing liners 12 in said bearing is a sleeve 13 to the lower end of which is connected the body 14 of the chuck. The body of the chuck is provided 65 with an upwardly extending boss 15 which

is bored for the reception of the end of the sleeve 13. The chuck body is secured to the end of the sleeve by means of a flanged nut 16 which has threaded engagement with the boss 15 and an annular flange on the sleeve 70 13, to rigidly secure the chuck to the sleeve. The chuck body 14 is provided with a downwardly extending stem 17, and 18 are radial slots or recesses in the body 14 and stem 17. These slots 18 do not extend through the 75 stem, as clearly shown in Figs. 6 and 9, so there is a web of metal 19 which connects the legs of the stem between the slots. Each of the four jaws K of the chuck is formed integrally with the lower end of an L-shaped 80 lever 20 having a tooth 21 for actuating the jaws, and which levers are seated within the slots 18 which form guides therefor, and are pivotally connected to the body by means of pins 22. 23 is the actuating spindle for the 85 chuck jaws which is slidably mounted in the sleeve 13, but is rotated therewith as herein-after described, and is provided at its lower end with an annular recess for the reception of the teeth 21 on the levers 20. 90 Mounted on the sleeve 13 is a beveled gear 24 which is connected to the sleeve 13 and the spindle 23 by means of keys 25, which pass through slots in the hub of the gear 24 and sleeve 13. The inner ends of these keys 95 engage key seats in the spindle 23 and are retained in position by a sleeve 26 surrounding the hub of the gear 24. The gear 24 is in driving relation with a bevel gear 27 on a shaft 28, which is continuously driven 100 by the driving mechanism of the machine, the connections of the parts being such that the spindle 23 and sleeve 13 together with the chuck are continuously rotated, while the sleeve and spindle are free to be moved 105 longitudinally relative to each other and the gear wheel 24.

Interposed between the gear wheel 24 and the liner 12 is the upper bearing, and surrounding the sleeve 13, is a sleeve 29 which is arranged to retain the gear wheel 24 on its seat on the central bearing and prevent upward movement of the gear 24 by friction when the sleeve 13 is raised.

Formed integrally with the liner 12 in the upper bearing is a cap having a threaded engagement with the shell 31, and 32 are balls between bearing disks between the cap and the shell.

33 is an adjustable stop nut threaded on the upper end of the sleeve 13 and which is arranged to limit the downward movement of the sleeve 13 and the chuck, and 34 is a lock nut for the nut 33.

Connected to the upper end of the spindle 125 23 by means of a pin 35 is a sleeve 36, which pin extends through holes in the sleeve and a slot in the spindle so that the sleeve is fixed against rotation with relation to the spindle, but is adapted to be adjusted longi- 130

tudinally therewith to determine the relative longitudinal movement between the sleeve 13 and the spindle 23, and consequently the spreading of the jaws K of the chuck.

5 This adjustment is effected by means of a shouldered screw 37 which has a threaded engagement with the spindle 23, while the shoulder of the screw is clamped against the top of the sleeve 36 by means of a locking 10 nut 38 having a threaded engagement with the sleeve 36. When it is desired to adjust the spindle 23 with relation to the sleeve 36, the nut 38 is loosened to free the screw 37 and the screw is then rotated to make the 15 adjustment, after which the nut is tightened to lock the screw.

Surrounding the sleeve 36 is a shell 39 which incloses ball bearings on opposite sides of an annular flange 40 on the sleeve 36, 20 the lower set being seated on a flange in the shell, while the upper set is retained in position by a cap 41 threaded on the shell 39. Interposed between flanged collars 42 and 25 43 surrounding the spindle 23 and within the shell 39 is a spring 44 which maintains the upper collar 42 against the lower end of sleeve 36 and collar 43 against the upper end of sleeve 13.

Pivots connected between standards 10 30 on a spindle 45 is a lever 46 having a fork at one end pivotally connected to the shell 39 by means of screw pins 47. The other end of this lever is also provided with fork members 48 which extend at right angles 35 to the fork connected to the shell 39 and straddle a lever 49 which is also pivoted to the shaft 45 between the standards 10. The fork members 48 are provided with screws 50 for varying the angle between the levers 40 46 and 49, the latter of which is provided with a roller 51 which is engaged by a cam 52 to lower the shell 39, and 54 is a spring 45 interposed between the lever 46 and a projection on one of the standards 10 to retain the shell 39 and chuck in their elevated positions.

Connected to the cylindrical portion of the shell 39 below its connection with lever 46 by means of a set screw 55 is a collar 56 50 to which is connected a rod 57, which is adapted to slide in guides on the front of the split bearing 11.

Slidably mounted on screws 58 connected to the rod 57 is the rod L² and which is held downwardly by a spring 59 interposed between the upper end thereof and a projection on the rod 57.

In the operation of the machine the gear 60 wheels 24 and 27 are continuously driven to rotate the chuck and its operating devices, while the shaft 53 is rotated in timed relation to the blank feeding devices, gummed strip feeding roller H and the strip shaping roller J.

The cam 52 is rotated in the direction of 65 the arrow indicated in Fig. 4 and during its first movement from the position shown the various parts will be moved downward until the nut 33 engages the disk above the balls 32 which will limit the downward movement 70 of the chuck, and at which time the jaws K will be within the blank D and sufficiently low enough to frictionally clamp the blank A between the ends of the jaws and the table 75 B, but not with sufficient pressure to mar the blank A. During the first downward movement of the chuck parts the turning in tool supporting member L¹ will engage the top of the stop pin M and arrest its downward movement, and the further downward movement 80 of the shell 39 will compress the spring 59, which is arranged to move the turning tool L into operative position when the pin M is withdrawn as previously described. In this further movement of the 85 shell 39 by the cam 52 the roller 51 will be further elevated until it passes onto the concentric portion 52^a thereof, and during such further movement after the downward movement of the chuck has been arrested, 90 the spindle 23 will be moved against the action of the spring 44 until the high point of the cam 52 engages the roller 51. This relative movement of the spindle 23 and sleeve 13 will rock the jaw levers 20 about 95 their pivot pins and spread the jaws to grasp the blank D. The box is finished as previously described during the time that the concentric portion 52^a is in engagement with the roller 51, and after the roller passes 100 from said cam portion the parts will be returned to the positions shown in Fig. 4 by the springs 44, 54 and 59.

The advantages of my invention result 105 from the provision of a chuck and operating devices which are arranged to be adjusted to cause the chuck to be moved to a predetermined position, together with adjusting means for determining the relative movement between the chuck moving means 110 and the chuck jaw actuating means so that the pressure on the several box forming blanks can readily be controlled.

A further advantage results from the provision of means for connecting the turning 115 tool to the chuck actuating shell which will avoid the necessity of perfect alinement between the chuck spindle and the guides for the turning tool holding bar or rod.

A still further advantage results from 120 the provision of a double armed lever for actuating the chuck which is provided with means for adjusting the angle of one arm with relation to the other.

Further, from the provision of a chuck 125 having jaws which are connected to a spindle which is arranged to be moved longitudinally with relation to the chuck

body, and which is so connected to the chuck jaws that the jaws will be opened and closed by the movement of the spindle.

Another advantage results from the provision of a chuck body having a stem with recesses for the jaw levers, in which the stem is provided with a web of metal connecting the guides for the jaw levers to form rigid supports for the jaws near their box engaging portions to maintain them in their radial positions with relation to the chuck body.

Having now fully described my invention, what I claim and desire to protect by Letters Patent is:—

1. A chuck having a body portion, a movable sleeve to which the body is connected, a plurality of jaws mounted in the body, a longitudinally movable spindle centrally mounted in the sleeve and body, actuating devices for the sleeve and spindle, actuating connections between the spindle and jaws, and actuating connections between the sleeve and spindle.

2. A movable chuck having a body portion, a reciprocating sleeve to which the body is connected, a support for the sleeve, a plurality of L-shaped jaw levers pivotally connected at one end to said body, engaging portions on the other ends of said levers, a longitudinally movable spindle centrally mounted in the sleeve and body, means to reciprocate the sleeve and spindle, connections between the levers and spindle for actuating the levers to open and close the jaws, and actuating connections between the sleeve and spindle.

3. A movable chuck having a body portion, a reciprocating sleeve to which the body is connected, a support for the sleeve, a plurality of L-shaped jaw levers pivotally connected at one end to said body, engaging portions on the other ends of said levers, a longitudinally movable spindle centrally mounted in the body, means to reciprocate the sleeve and spindle, an annular recess in the spindle, a tooth on each lever seated in said recess, and actuating connections between the sleeve and spindle.

4. A paper box machine having a sleeve mounted for rotation and reciprocation, a chuck body connected to said sleeve, jaws mounted in the chuck body, a spindle mounted in the sleeve and arranged to move longitudinally with relation thereto, actuating connections between the spindle and the jaws, means for rotating the sleeve, and a single means for reciprocating the spindle and sleeve as well as the spindle with relation to the sleeve to actuate the jaws.

5. A paper box machine having a sleeve mounted for rotation and reciprocation, a chuck body connected to said sleeve, jaws pivotally mounted in the chuck body, a spindle mounted in the sleeve and arranged to

move longitudinally with relation thereto, actuating connections between the spindle and the jaws, means for rotating the spindle and sleeve, and a single means for reciprocating the spindle and sleeve as well as the spindle with relation to the sleeve to actuate the jaws.

6. A paper box machine having a sleeve mounted for rotation and reciprocation, a chuck body connected to said sleeve, jaws mounted in the chuck body, a spindle mounted in the sleeve and arranged to move longitudinally with relation thereto, actuating connections between the spindle and the jaws, means for rotating the sleeve, means for reciprocating the sleeve as well as the spindle with relation to the sleeve, and adjustable stop means for the sleeve for limiting the movement of the sleeve and permit the spindle to move relative thereto to actuate the jaws.

7. A paper box machine having a sleeve mounted for rotation and reciprocation, a chuck body connected to said sleeve, jaws mounted in the chuck body, a spindle mounted in the sleeve and arranged to move longitudinally with relation thereto, actuating connections between the spindle and the jaws, means for rotating the sleeve, means for reciprocating the sleeve as well as the spindle with relation to the sleeve to actuate the jaws, and a turning-in tool arranged to be actuated by the spindle reciprocating means.

8. A paper box machine having a sleeve mounted for rotation and reciprocation, a chuck body connected to said sleeve, jaws mounted in the chuck body, a spindle mounted in the sleeve and arranged to move longitudinally with relation thereto, actuating connections between the spindle and the jaws, means for rotating the sleeve, means for reciprocating the sleeve as well as the spindle with relation to the sleeve, a two part lever connected to the sleeve to move the sleeve in one direction, a cam for moving the lever in the last mentioned direction, spring means for returning the sleeve and lever, and adjusting means for adjusting one part of the lever with relation to the other part thereof.

9. A paper box machine having a sleeve mounted for rotation and reciprocation, a chuck body connected to said sleeve, jaws mounted in the chuck body, a spindle mounted in the sleeve and arranged to move longitudinally with relation thereto, actuating connections between the spindle and the jaws, means for rotating the sleeve, means for reciprocating the sleeve as well as the spindle with relation to the sleeve to actuate the jaws, and adjusting devices in the reciprocating means between the spindle and sleeve.

10. A paper box machine having a chuck

- mounted on a sleeve, jaws in said chuck, a spindle in the sleeve connected to the jaws, means for rotating the sleeve, an adjustable stop for the sleeve, reciprocating devices connected to the spindle, and a spring interposed between the sleeve and spindle arranged to move the sleeve and chuck against the stop and then move the spindle with relation to the sleeve to actuate the jaws.
- 10 11. A paper box machine having a chuck mounted on a sleeve, jaws in said chuck, a spindle in the sleeve connected to the jaws, means for rotating the sleeve, an adjustable stop for the sleeve, reciprocating devices connected to the spindle, adjusting means between the spindle and the reciprocating devices, and a spring interposed between the sleeve and spindle arranged to move the sleeve and chuck against the stop and to
- 15 permit the spindle to move with relation to the sleeve to actuate the jaws.
12. A paper box machine having a chuck mounted on a sleeve, jaws pivotally mounted in said chuck, a spindle in the sleeve connected to the jaws, means for rotating the sleeve, an adjustable stop for the sleeve, reciprocating devices connected to the spindle, and a spring interposed between the sleeve and spindle arranged to move the sleeve and chuck against the stop and to permit the spindle to move with relation to the sleeve to actuate the jaws.
13. A device of the character described comprising a bearing, a sleeve slidably and 35 rotatably mounted therein, a spindle slidably mounted in the sleeve, gearing for rotating the sleeve and spindle in unison, a chuck body connected to the sleeve, movable jaw levers mounted in the chuck body, actuating 40 connections between the jaws and the spindle, a spindle reciprocating member, and a spring interposed between the spindle and sleeve.
14. A device of the character described comprising a bearing, a sleeve slidably and 45 rotatably mounted therein, a spindle slidably mounted in the sleeve, gearing for rotating the sleeve and spindle in unison, a chuck body connected to the sleeve, jaw levers pivoted to the chuck body, actuating 50 connections between the jaws and the spindle, a spindle reciprocating member, and a spring interposed between the spindle and sleeve.
15. A device of the character described, 55 comprising a bearing, a sleeve slidably and rotatably mounted in the bearing, a chuck body connected to the spindle, movable jaw levers in the body, a spindle slidably mounted in the sleeve and arranged to rotate there- 60 with, actuating connections between the jaw levers and the spindle, a shell surrounding the spindle, a thrust bearing member within the shell, an adjustable connection between the shell and the spindle, and a spring inter- 65 posed between the shell and sleeve.
16. A device of the character described comprising a bearing, a sleeve slidably and rotatably mounted in the bearing, a chuck body connected to the spindle, movable jaw levers in the body, a spindle slidably mounted in the sleeve and arranged to rotate there- 70 with, actuating connections between the jaw levers and the spindle, a shell surrounding the spindle, a thrust bearing member within the shell, an adjustable connection between the shell and the spindle, a spring interposed between the shell and sleeve, a slide seated in guides, a connection between the slide and the shell, and a turning-in tool yieldingly mounted on the slide.
17. A device of the character described comprising a bearing, a sleeve slidably and rotatably mounted in the bearing, a chuck body connected to the spindle, movable jaw levers in the body, a spindle slidably mounted in the sleeve and arranged to rotate there- 75 with, actuating connections between the jaw levers and the spindle, a shell surrounding the spindle, a thrust bearing member within the shell, an adjustable connection between the shell and the spindle, a spring interposed between the shell and sleeve, a slide seated in guides, a connection between the slide and the shell, and a turning-in tool yieldingly mounted on the slide.
18. A chuck actuating device comprising a rotating and sliding sleeve, a reciprocating spindle mounted in the sleeve for actuating 80 chuck members, a spindle reciprocating shell mounted on the spindle, a second sleeve mounted on the spindle having thrust members for engaging the shell, a driving connection between the second sleeve and the 85 spindle, and an adjustable connection between the spindle and the second sleeve for adjusting the slide along the spindle.
19. A chuck having a body with a central projection on one face thereof, a central bore extending into the body from the other side, a plurality of radial slots in the body on the stem side communicating with the bore, a similar number of longitudinal slots in the periphery of the projection in line with and communicating with the radial slots, an L-shaped jaw lever in each radial slot and the longitudinal slot in line therewith, said levers being pivoted to the body at the outer ends of one of the legs thereof, 100 clamping devices on the ends of the other legs, a jaw lever actuating spindle in the bore, and a connection between said spindle and each jaw lever at the junctions between the legs of the levers.
- 120 In testimony of which invention, I have hereunto set my hand, at Pikesville, Md., on this 22nd day of January, 1921.
- 125
